UNITED STATES PATENT OFFICE.

GEORGE JAMES MANSON, OF TORONTO, ONTARIO, CANADA.

RETRACTOR AND SPRINKLER FOR FIBER-PRESS DIES.

1,413,179.

Specification of Letters Patent. Patented Apr. 18, 1922.

Application filed May 3, 1919. Serial No. 294,628.

(GRANTED UNDER THE PROVISIONS OF THE ACT OF MARCH 3, 1921, 41 STAT. L., 1313.)

To all whom it may concern:

Be it known that I, GEORGE JAMES MANSON, a subject of the King of Great Britain, and resident of the city of Toronto, in Province of Ontario, Dominion of Canada, have invented certain new and useful Improvements in Retractors and Sprinklers for Fiber-Press Dies, of which the following is a specification.

10 This invention relates to improvements in retractor and sprinkler for fiber press dies, and the objects of the invention are to provide a simple and effective means for retracting a pressed fiber sheet or article from 15 between the pressing dies and for sprinkling the surface of the dies.

Further objects are to generally improve and simplify the construction of the device to better adapt it to perform the functions 20 required of it, and it consists essentially of the improved construction hereinafter described in detail in the accompanying specification and drawings.

The drawings show a set of dies and apparatus for carrying out the sprinkling operation.

In the drawings:

Figure 1 is a sectional elevation of a fiber press.

30 Figure 2 is a sectional plan.

Figure 3 is a cross sectional elevation.

Figure 4 is a sectional detail of the water feeding means.

Figure 5 is a sectional detail of the retractor and carriage for the sprinkling means.

Figure 6 shows the same parts as in Figure 5 with the retractor and carriage beneath the dies.

40 Figure 7 is a sectional detail of the dies closed.

Figure 8 is a sectional detail of a portion of the cam track controlling the sprinkling device.

45 Figure 9 is a sectional view through the controlling valve.

In the drawings like characters of reference indicate corresponding parts in all the figures.

50 Referring to the drawings, A represents a fiber press having an upper die B, a lower

die C, and a side or wall die D which are operated by suitable hydraulic means to press a sheet of fiber in the manner well known in the art. In the embodiment illustrated the lower die C is connected to and actuated by hydraulic cylinders 10 which actuate plungers 11 connected to a platform 12 supporting the die. The upper die B is connected to a platform 13 fixedly mounted 55 on the side posts 14, the lower extremities of which are connected by a cross bar 15 to the cylinders 10. The side or wall die D is also actuated by hydraulic means such as the cylinder 16 having plungers 17 connected to opposite sides of the wall die. 60

In the present operation the closed position will be as indicated in Figure 7 and the open position as shown in Figure 1. The pulp or other fiber stock to be pressed into a 70 sheet or other article may be fed into the conduit 18 which opens into a port 19 in the wall die, the retraction of the wall die over the die B cutting off the port and supply of fiber at the proper point. It will be understood, however, as far as the present invention is concerned the dies and method of operating the same will be of any suitable character. 75

E represents a sprinkling device reciprocable between the dies B and C when they are separated. The form of sprinkling device I have shown comprises a transversely extending pipe 20 perforated in rows along the top and bottom whereby when the water 80 pressure is on, the surface of both the upper and lower dies will be sprinkled. This pipe is supplied with water with a suitable flexible connection including a telescopic supply pipe 21 extending through a gasket 22 in 85 the end of the pipe 20 connected to a suitable supply pipe 23. The pipe 20 is supported from a reciprocable retractor carriage F having wheels 24 which run in a track 25, the movement of the retractor carriage being controlled by suitable means such as the driving pinion 26 engaging the rack 27 connected to the carriage, the rack receiving additional support from suitable rollers 28. 90

100 Means are provided for stripping the pressed sheet from the retractor carriage

when outside the die whereby it may be transferred to a suitable conveyor. These means comprise a pivoted stripping member 31 pivotally mounted on the cross shaft 32 and adapted to assume the inclined position shown in Figure 5 as the carriage F passes beneath it whereby on the return motion of the carriage it will strip the sheet of pulp 33 therefrom and permit it to drop onto the 10 conveyor G.

The operation of the sprinkling device is controlled in such a way as to cause it to operate only when it is moving on the return direction across the face of the dies. It is 15 not desirable that the sprinkling should take place on the forward motion, since while the sprinkler is moving in this direction the pressed sheet will be held against the surface of the die. The controlling 20 means which I have shown comprise a valve 35 of any suitable type having a stem 36 normally spring held in open position by means of a spring 37 extending between the collar 38 on the stem 36 and the top of the 25 valve casing 39. The stem 36 carries a roller 40 at the top controlled by a cam track 41. This cam track 41 includes a lower track 42 having a central aperture through which the stem 36 may pass; but through which 30 the roller 40 may not pass, and an upper track 43 which projects beyond the upper track and is formed at one portion with an inclined section 44 which brings it into alignment with the lower track.

35 On the inward movement the roller 40 runs on the lower track 42; when it reaches the end of this track the spring 37 causes the valve stem to move outwardly, opening the valve and causing the sprinkler to operate on the return movement. While the 40 sprinkler is operating the roller 40 runs on the track 43, passes down the inclined portion 44 to the lower portion 45 of the track 43. On the return movement the roller is 45 prevented from passing up the inclined portion 44 by means of a spring trap member 46 hinged to the end of the track 42 and spring held in alignment therewith as shown in Figure 8, whereby when the trap member 50 is in position there will be no passage from the section 45 of the track 43 to the main portion thereof, the trap, however, being free to swing downwardly to permit of movement from the upper track to the lower track.

55 The operation of the press takes place in the usual way, the pulp stock being fed between the dies and the pressure being exerted by hydraulic means, while the water is 60 withdrawn through the foraminous surface of the dies, this surface being of any usual character and including a suitable number of grooves and perforated plates of a character well known in the art which will en-

able the water to be strained, leaving the 65 pulp or fiber between the dies.

Finally the pressed sheet or article is caused by suction to adhere to the upper die when the dies are separated, suction being exerted through the passageways or ports 70 in the die through which the water was withdrawn. When the sheet is in this position the retractor F comes between the dies, the suction is then released to permit the sheet to drop onto the retractor carriage, 75 and on withdrawal of the retractor carriage the sprinkler operates as previously described to sprinkle the surface of both the upper and lower die, the sprinkling operation ceasing as soon as the roller passes down the inclined portion 44 to the lower portion 80 45 of the track 43. When the retractor carriage reaches its outermost position the article is stripped therefrom by means of the pivoted stripping member 31.

85 As many changes could be made in the above construction, and many apparently widely different embodiments of my invention, within the scope of the claims, constructed without departing from the spirit 90 or scope thereof, it is intended that all matter contained in the accompanying specification and drawings shall be interpreted as illustrative and not in a limiting sense.

95 What I claim as my invention is:

1. In a fiber press, the combination with the dies, of sprinkling means adapted to enter between the same.
2. A fiber press having means for sprinkling the die surface thereof.
3. In a fiber press and in combination, a pair of dies, sprinkling means adapted to enter between the dies when apart, and means for supplying the sprinkling means with fluid while moving.
4. The arrangement according to claim 3, in which sliding telescopic water supply conduits are provided.
5. In a fiber press and in combination, a die, a sprinkler movable across the face of the die, and controlling means for the sprinkler adapted to cause it to operate only when moving in one direction across the face of the die.
6. In a fiber press and in combination a pair of dies, means for causing the pressed article to adhere to the surface of the upper die upon separation of the dies, a retractor adapted to enter between the dies and receive the pressed article, and a sprinkler also adapted to enter between the dies with the retractor, and controlling means for the sprinkler adapted to cause the same to separate on the return movement only.
7. The arrangement according to claim 6, in which the controlling means comprises a valve, a stem therefor and a cam track controlling the movement of the stem.

8. In a fiber press, and in combination, a pair of dies, a retractor adapted to enter between the dies when apart, a pivoted stripping member adapted to strip the pressed article from the retractor.

9. In a fiber press and in combination, a pair of dies, a retractor carriage adapted to reciprocate between the dies when apart, a track supporting the carriage, and a strip-

ping member adapted to strip the pressed article from the carriage as it reciprocates.

In witness whereof I have hereunto set my hand in the presence of two witnesses.

GEORGE JAMES MANSON.
